GRIEF COLLAR

Harry H. Clark, Los Angeles, Calif., assignor to
 The National Supply Company, Pittsburgh, Pa.,
 a corporation of Pennsylvania

Application August 4, 1939, Serial No. 288,312

14 Claims. (Cl. 308—4)

This invention relates to grief collars, and more particularly to a method of forming and construction of grief collars particularly applicable for use in drilling apparatus of the type employed in the rotary system of drilling wells and to an improved form of grief collar for use in conjunction with the drill string or pipe to protect the same against wear.

In the rotary process of drilling wells there is customarily used a drill string formed of a plurality of sections of pipe secured together by means of couplings. In many cases the couplings utilized for securing together the sections of pipe are of larger diameter than the pipe. As the drill string is rotated in the rotary process of drilling wells, the pipe and such couplings receive wear due to the rubbing thereof against the side of the hole or against the side of the casing used in the hole. Unless some adequate means of protection is provided, the pipe and the couplings are subjected to very rapid wear particularly enhanced by deviations of the well hole from a straight hole. As all well holes of any appreciable depth deviate considerably from a straight line, the wear upon these pipes and couplings becomes very much more rapid at the points of deviation of the hole from the straight.

There has heretofore been utilized in the rotary process of drilling wells rubber collars which are interposed between the drill stem and the casing to protect the drill pipe and couplings from wear against the casing. It has been found, however, that these rubber collars are not satisfactory for use below the casing and in direct contact with the formation being drilled. When the rubber drill collars are utilized in the open hole or in direct contact with the formation, they are of very short life due to the fact that the rubber does not stand the action against the formation.

It is therefore an object of this invention to provide a protecting collar commonly known in the art as a grief collar applicable for use in connection with a drill stem, which is particularly applicable for open hole use and which will effectively operate in direct contact with the well formation.

Another object of this invention is to provide a grief collar having a wear member which is supported upon a well pipe in such manner that the strength and rigidity of the drill pipe or string is not weakened and so that a region of high stress concentration in the pipe is avoided.

Another object of this invention is to provide a grief collar comprising a metallic wear member mounted on a well pipe by means of a layer

of resilient material, whereby the grief collar acts as a resilient buffer to cushion shock loads.

Another object of my invention is to provide a grief collar which will not restrict materially the normal flexure of the drill string.

Other objects and advantages of this invention it is believed will be apparent from the following detailed description of a preferred embodiment thereof as illustrated in the accompanying drawing.

In the drawing:

Figure 1 is a perspective view showing a grief collar embodying my invention.

Figure 2 is a transverse section of the grief collar as illustrated in Figure 1.

Figure 3 is a sectional elevation taken substantially on the line 3—3 of Figure 2.

In each of Figures 1, 2 and 3 the grief collars embodying my invention are illustrated as adapted to a section of pipe.

Figure 4 is a transverse section of a modified form of grief collar embodying my invention likewise illustrating the same as adapted to a section of pipe.

In the drawing 10 indicates a section of well pipe or "drill string" of any desired or preferred type as utilized in the rotary process of drilling. As is well known in the art, sections or length of drill pipe 10 are joined together by suitable couplings (not shown) to form the drill string. As the term "well pipe" will hereinafter be utilized, it refers to the drill pipe or couplings or tool joints or any other of the well known elements utilized to make up the drill string as the grief collar embodying my invention may be advantageously employed in connection with any such elements of the drill string.

The grief collar embodying my invention is composed of a metallic wear member 11 which is generally formed of two half sections or segments 12 and 13. The wear member or sleeve 11 may be formed of any suitable or desirable material but is preferably formed of steel to provide a hardened wearing surface 14. Thus the wear member 11 may be formed of high manganese steel which is very hard and has the peculiar characteristic of becoming harder as it is worked.

The wear member 11 is formed to provide a cavity 15 around the well pipe 10. This cavity 15 is filled with a sleeve of rubber 16. The rubber sleeve 16 is retained in the cavity under compression as, for example, will be apparent from the following illustrative example of the method of application and compression of the sleeve 16 between the wear member 11 and the well pipe

10. In one illustrative example utilizing a well pipe of a $4\frac{1}{2}$ inches outside diameter the inside diameter D of the cavity 15 is made $5\frac{1}{8}$ inches. The rubber sleeve 16 before compression has a thickness of $\frac{3}{8}$ inches. The sleeve 16 is of substantially the same length as the cavity 15, the outer ends of the cavity being defined by inwardly directed walls 25.

The rubber inserts 16 are placed in position within the segments 12 and 13. The segments 10 are then brought into position on opposite sides of the pipe 10 with the rubber contacting the outer surface of the pipe. By the use of suitable clamps the two segments are compressed together to apply an initial compression in the sleeve 16 which substantially amounts to compressing the thickness of the rubber sleeve down to $\frac{5}{16}$ inches or thereabouts, thus imparting a very material compression to the rubber. The two segments 12 and 13, while held clamped to the pipe and to the sleeve, are then welded together at the longitudinal seams 17 and 18 whereby the sleeve 16 is maintained in compression. Thus a compressed sleeve of rubber is maintained between the wear element 11 and the well pipe 10. As this sleeve is tightly compressed against the pipe, it follows all possible irregularities of the pipe contour and firmly fixes the wear sleeve 11 in position upon the pipe against longitudinal movement along the length of the pipe.

In the form of grief collar illustrated in Figures 1, 2 and 3 the segments 12 and 13 at their adjacent longitudinal edges 19 are provided with inwardly projected ribs 20 which cooperate with walls 25 to act as a means for confining the rubber sleeve 16 against extrusion during the process of compressing the same. A welding cavity 21 is thus formed between the segments 12 and 13 which is free of rubber. The welding cavities 21 are also provided with tapered walls 22 which facilitate the process of forming the longitudinal welds 17 and 18. It is preferable during the formation of the longitudinal welds 17 and 18 to place in the bottom of the cavity some form of material such as asbestos or the like to prevent excessive heating of the well pipe 10. Thus the welds 17 and 18 may be formed to maintain the segments 12 and 13 together without danger of causing the same to adhere to, or to be welded to, the well pipe, thus weakening the pipe at such welded points.

If desired, one or more recesses 23 may be formed from the surface 14 in the wear member 11, which recesses 23 are of known depth when the grief collar is installed in position. These recesses 23 then form a means of determining the amount of wear of the grief collar by checking the depth thereof from the surface 14 so that the amount of wear along the surface 14 may be determined to enable the driller to know when such grief collar should be replaced or has become dangerously thin due to wear.

In the modified form of my invention illustrated in Figure 4, similar parts have been designated with similar numerals with the addition of the exponent "a" thereto. In this form of my invention, the sleeve 16a which is positioned in the cavity 15a is formed as a slit ring, or may be formed as a solid sleeve slipped over the pipe in any suitable or desirable manner. The solid ring then is fitted into the cavity 15a by positioning the two segments 12a and 13a of the wear member 11a over the continuous ring. The two segments 12a and 13a are then compressed against the sleeve 16a by the use of

suitable clamps, not shown, until the lateral edges 19a meet in metal to metal contact, thereby limiting the compression of the rubber.

In this form of my invention the mating edges 19a between the segments 12a and 13a are formed to provide a lap-joint by providing ribs 20a which fit within recesses 24a formed in the adjacent edge 19a of the opposite segment. Thus the ribs 20a, in addition to forming means for preventing the extrusion of the rubber sleeve 16a, also provide a means for closing the bottom of the welding recesses 21a.

In both forms of the grief collar embodying my invention the metallic wear member as resiliently carried on the pipe acts as a resilient buffer. As no welds are required to maintain the wear member on the pipe and no welds are made into the well pipe, the same is not weakened. As the wear member is not directly mounted on the pipe but there is interposed between it and the well pipe the resilient rubber sleeve, there is no high stress concentration in the pipe adjacent the grief collar but normal flexing is permitted.

It will be obvious that the specific illustration hereinabove given is given merely for the purpose of enabling one skilled in the art to determine the exact method of carrying out my invention and is not intended to in any way limit my invention to any of the sizes, proportions or degrees as therein specified.

The grief collar embodying my invention furthermore may be mounted on any section of the well pipe intermediate the couplings or tool joints or may be mounted adjacent or directly upon the coupling or tool joint if desired. Furthermore, the grief collar may be mounted on the pipe midway between couplings or tool joints in order to prevent wear on the pipe and decrease the amplitude of oscillation of the pipe as it is rotated in the hole.

Having fully described my invention, it is to be understood that I do not wish to be limited to the details herein set forth, but my invention is of the full scope of the appended claims.

45. I claim:

1. A grief collar for a well pipe, comprising an outer metallic wear member surrounding the pipe and supported thereon by means of a layer of rubber-like material confined under compression between the wear member and the pipe.

2. A grief collar for a rotating well pipe, comprising a steel sleeve surrounding the pipe and supported thereon by means of a layer of rubber confined under compression between the steel sleeve and the pipe.

3. In a grief collar for a well pipe, the combination of a metallic sleeve surrounding the pipe and comprising a plurality of segments, a layer of rubber-like material within each segment, means to confine the rubber-like material longitudinally and laterally within its respective segment, the segments being welded together to maintain the rubber-like material under compression between the sleeve and the pipe.

60. 4. As an article of manufacture, a grief collar for a well pipe, comprising a cylindrical steel sleeve surrounding the pipe, and formed as a pair of cooperating halves, a rubber insert associated with each of said halves, means to confine each rubber insert longitudinally within said sleeve, the halves being integrally joined by welding to maintain the rubber under compression between the sleeve and the pipe.

5. In a grief collar for a well pipe, the combination of an outer metallic wear member surround-

ing the pipe comprising two substantially semi-cylindrical segments, an inner layer of resilient material interposed between the segments and the pipe, means to confine the resilient material longitudinally within said segments, and fastening means adapted to secure said segments together whereby the resilient material is maintained under compression.

6. In a grief collar for a well pipe, the combination of a cylindrical steel wear member surrounding the pipe and formed as a pair of cooperating halves, inwardly directed ribs adjacent the lateral faces of each of said halves, a resilient liner disposed within each of said cooperating halves between said ribs, fastening means comprising a weld integrally joining said cooperating halves together along said ribs, said fastening means acting to maintain said resilient liners in compression between the cooperating halves and the pipe.

7. In a grief collar for a well pipe, the combination of a cylindrical metallic wear member surrounding the pipe and formed as a pair of cooperating segments, an annular sleeve of resilient material interposed between the segments and the pipe, the adjacent lateral faces of said segments meeting in direct contact to limit extrusion of the resilient material, means to confine the resilient material longitudinally within said segments, and fastening means adapted to secure said segments together along their lateral faces.

8. A grief collar for a well pipe, comprising an outer metallic wear member encircling the well pipe, and a resilient non-metallic member interposed between the wear member and the well pipe, the resilient non-metallic member being the sole means for supporting the outer metallic wear member on the well pipe.

9. The method of forming a grief collar for a well pipe, comprising placing a pair of cooperating segments of a metallic sleeve on opposite sides of the pipe, positioning one or more rubber inserts between the segments and the pipe, clamping the cooperating segments together to compress the rubber inserts, and fastening the segments while they remain clamped together in order to maintain the rubber inserts under initial compression.

10. The method of making a grief collar for a well pipe, comprising placing a pair of cooperating segments of a metallic sleeve on opposite sides of the pipe, positioning a layer of resilient mate-

rial in pockets formed in the segments, clamping the cooperating segments together to compress the resilient material between the segments and the pipe, and fastening the segments while they remain clamped together in order to maintain the resilient material under initial compression.

11. The method of forming a grief collar for a well pipe, comprising positioning a layer of rubber-like material around the pipe, clamping a pair of cooperating metallic segments on opposed sides of the pipe to compress the rubber-like material between the metallic segments and the pipe, and welding the adjacent lateral faces of the segments together while they remain clamped together in order to form an integral wear member surrounding the pipe.

12. The method of making a grief collar for a well pipe, comprising placing a pair of cooperating segments of a metallic sleeve on opposite sides of the pipe, positioning a layer of resilient material between the segments and the pipe, bringing the cooperating segments together initially until their adjacent lateral faces meet to limit the compression of the resilient material, and securing the segments together against separation in order to maintain the resilient material under initial compression.

13. A grief collar for a well pipe, having in combination a pair of cooperating segments adapted to encircle the pipe, inwardly directed ribs formed on each segment along its lateral edges, inwardly directed walls formed on each segment along its upper and lower ends, the said ribs and walls cooperating to define a cavity within each of said segments, a resilient liner disposed within each of said cavities, the segments being welded together along their adjacent ribs whereby the resilient liners are maintained under initial compression between the segments and the pipe, and are confined against extrusion by said ribs and walls.

14. In a grief collar for a well pipe, the combination of a metallic sleeve surrounding the pipe and comprising a plurality of cooperating segments, a layer of resilient material interposed between the segments and the pipe and confined against lateral expansion, and means securing the segments together against separation to maintain the resilient material under initial compression between the sleeve and the pipe.
